Application filed February 8, 1928. Serial No. 25,258. Term of patent 14 years.

To all whom it may concern:

Be it known that I, EDWARD KARFIOL, a citizen of the United States, residing in Brooklyn, in the county of Kings and State of New York, have invented a new, original, and ornamental Design for a Doily, of which the following is a specification, reference being made to the accompanying drawing, forming part thereof, in which the figure represents a face view of a doily, showing my new design.

As indicated in the drawing one-fourth of the ornamental part of the doily and the outline thereof is detailed in full lines, while the other three-fourths which would be a duplication of the ornamental parts illustrates the border lines of the ornamental area in dotted lines.

I claim:

The ornamental design for a doily as shown and described.

EDWARD KARFIOL.
